DEMODULATOR SYSTEM FOR TIME
MODULATED PULSES

Max G. Hollabaugh, Jackson Heights, N. Y., assignor to Federal Telecommunication Laboratories, Inc., New York, N. Y., a corporation of Delaware

Application April 18, 1946, Serial No. 663,126

9 Claims. (Cl. 250—27)

1

This invention relates to demodulators for time modulated pulse systems, particularly of the multi-channel type.

Multi-channel time modulated pulse systems have been proposed in which pulses of different channels are interleaved and spaced with respect to regularly repeated marker pulses or signals so as to form a single train.

An object of the present invention is the provision of an improved demodulator for time modulated pulse systems.

Another object of the present invention is the provision of a combined demodulator and channel selector for multi-channel time modulated pulse systems.

A feature of the present invention is the provision of a combined channel selector and demodulator characterized by simplicity and reliability.

Another feature of the present invention is the provision of a demodulator for time modulated pulses whose characteristics vary substantially linearly with the time modulation of the pulses.

Other and further objects of the present invention will become apparent and the invention will be best understood from the following description of an embodiment thereof, reference being had to the drawings, in which:

Fig. 1 is a block diagram of a multi-channel time modulated pulse receiver embodying my invention;

Fig. 2 is a schematic diagram of a selector-demodulator embodying my invention; and

Fig. 3 is a set of curves used in describing the operation of the selector-demodulator of Fig. 2.

Referring now to Fig. 1, the receiver system there shown is of the type particularly adapted for the reception of pulse trains of multi-channel time modulated pulses such as for example, as illustrated in curve A, Fig. 3, where a series of signal pulses 1, 2, 3, 4, etc., each forming part of a separate channel, follow a marker pulse 5. These series are repeated as shown in said figure to form part of a continuous train with the signal pulses being varied between the limits indicated by the dotted lines on either side thereof. The signal pulses are equally spaced from each other in their unmodulated position.

Such trains of pulses may be used to modulate a carrier wave which may be radiated and thereafter received on an antenna 6 and fed to a receiver 7 where the carrier frequency is removed. The output of receiver 7 is fed through a plurality of channels 8, 9, 10, 11, each channel being

designed to receive pulses belonging to a separate one of the pulse channels 1—4 respectively. For control purposes, an additional channel 12 is provided at the output of the receiver 7, which channel is used to select the marker pulse as for example, by means of a pulse width or time duration discriminator or other type of marker selector 13, the output of the marker selector being in turn used to synchronize a rectangular wave generator 14, whose output is then fed over a line 15 to a delay device 16 in channel 8. The delay device 16 is adjusted for the purpose of delaying the control wave output of generator 14 to determine which of the particular channels is to be selected in the selector-demodulator 17 to which the delayed rectangular wave from delay device 16 is fed. For example, in channel 8, the selector-demodulator 17, which receives all the pulses, only accepts those of the desired channel which may be for example, 2; and demodulates the time modulation of the pulses of channel 1 and feeds its resulting output to any suitable utilization device 18. The other signal channels 9, 10 and 11 are similar to channel 8 in that they have a corresponding delay device 16, selector-demodulator 17 and suitable utilization device 18; but the delays in the separate channels differ to select different pulse channels.

The operation of the selector-demodulator 17 will be best understood from the illustration of Fig. 2 and the curves of Fig. 3. Rectangular wave generator 14 produces rectangular wave control pulses 19 having a repetition frequency equal to the repetition frequency of the marker pulses 5, and having a sufficient duration to accommodate any signal pulse over its entire range of time displacement due to modulation. For example, in one given case, the signal pulse had a width of a half microsecond and had a displacement of plus or minus one microsecond. The total time elapsing to cover the signal pulse with its maximum displacement is a period of two and one-half microseconds. The width of the rectangular wave pulse 19 was four microseconds and was adjustable. The spacing between pulses at their central position was five microseconds. The rectangular pulses 19 are delayed a sufficient amount in delay device 16 to select the particular channel desired. For example, referring to curve B, Fig. 3, the delay in delay device 16 was such as to select channel 2 as will be seen since the rectangular pulse 19 substantially coincides with pulse 2 and covers the maximum time displacement of said pulse in either direction. 55 The rectangular pulse 19 and the signal pulses

are used to control the output of an electron discharge device as for example by being fed to the second and first grids respectively of a pentode 20 in the selector-demodulator 17. The pentode 20 is so biased that neither the rectangular pulse alone nor the signal pulse alone is sufficient to cause the flow of plate current, as is indicated by the conductivity levels 21 and 22 associated with curves A and B respectively. When, however, said rectangular wave pulse 19 coincides with one of the signal pulses, such as for example, signal pulse 2, the pentode 20 conducts and by the use of suitable shaping means consisting of condenser 23, resistors 24 and 25, the plate current is then so shaped as to produce a negative pulse 26, curve 3, Fig. 3 at the first grid of a second pentode 27 in the selector-demodulator 17. Pulse 26 has a very steep leading edge 28 and a substantially logarithmically-declining trailing edge 29. The rectangular pulses 19 which are applied to the second grid of pentode 20 are also simultaneously applied to the second grid of pentode 27. Pentode 27 has a low cut-off level as indicated by the line 30 so that the rectangular pulse 19 is sufficient to start pentode 27 conducting. When, however, pulse 26 is applied to the first grid of pentode 27, pulse 26 has so large an amplitude that it immediately cuts off pentode 27 despite the fact that rectangular pulse 19 is still being applied in a positive vectorial direction to the second grid of pentode 27. The resultant output of pentode 27 consists of pulses 31, whose leading edge coincides with the leading edge of pulses 19 and whose trailing edge coincides with the leading edge of pulses 26. Since the leading edge of pulse 26 coincides with the leading edge of the signal pulse, as for example, pulse 2 in Fig. 3, the leading edge of pulse 26 will vary according to the time modulation of the signal pulse and likewise the trailing edge of pulse 31 will vary with the time modulation of the signal pulse. This is represented in Fig. 3. For example, pulse 2 in the first series is represented as being in its intermediate or unmodulated position and the resultant output pulse 31 has a given width. Pulse 2a in the second series is represented close to one extreme of modulation and the resultant output pulse 31a is considerably wider than pulse 31. Pulse 2b in the third series is shown at the other extreme of modulation and the resultant output pulse 31b is narrower than pulse 31. Accordingly, the duration of the output pulses 31 varies in accordance with the time modulation of the signal pulses. It will be seen that this variation is linear and is not determined by the transfer characteristics of the pentode 27. The output pulses 31 may then be fed to any suitable integration device such as for example, a low pass filter 32 and then to the utilization device 18 which may be for example, an amplifier and loud speaker system.

While I have described above the principles of my invention in connection with specific apparatus, it is to be clearly understood that this description is made only by way of example and not as a limitation on the scope of my invention.

I claim:

1. A demodulator for time modulation pulse systems in which a signal pulse varies from a given time position according to its modulation, comprising a control pulse source producing pulses of constant duration, said duration being at least as great as the maximum range of time displacement of the signal pulses due to modu-

lation, means for timing one of said control pulses substantially to coincide in time with a corresponding signal pulse so that the control pulse has a fixed time relationship to the unmodulated position of the signal pulse and covers the entire range of time displacement thereof, means responsive to the coincidence of the timed control pulse and the signal pulse to produce a pulse having a relatively steep wave front, current-control means responsive to the timed leading edge of the control pulse for initiating the flow of current and responsive to the steep pulse for halting the flow of current, whereby the resultant output pulse from said current-control means varies in duration in accordance with the time modulation of the signal pulse.

2. A demodulator for time modulation pulse systems of the type in which a marker signal is followed by a signal pulse which signal pulse varies from a given time position with respect to the marker signal according to its modulation, comprising means responsive to the marker pulse for producing a control pulse of constant duration, said duration being at least as great as the maximum range of time displacement of the signal pulses due to modulation, means for delaying said control pulse to substantially coincide in time with the signal pulse so that the control pulse has a fixed time relationship to the unmodulated position of the signal pulse and covers the entire range of time displacement thereof, means responsive to the coincidence of the delayed control pulse and the signal pulse to produce a pulse having a steep wave front, current-control means responsive to the leading edge of the delayed control pulse for initiating the flow of current and responsive to the steep pulse for halting the flow of current, the resultant output pulse from said current-control means varying in duration in accordance with the time modulation of the signal pulse, and integrating means for translating the duration of said output pulse into an amplitude characteristic.

3. A demodulator according to claim 2 wherein said control pulse producing means is comprised of a rectangular wave generator.

4. A demodulator according to claim 2 wherein said means responsive to the coincidence of the delayed control pulse and the signal pulse comprises an electron discharge device having at least one control element, means for biasing said device so that the control pulse alone or the signal pulse alone is of insufficient amplitude to cause said device to conduct, but both signal pulse and control pulse together are capable of causing conduction of said device, means for applying said delayed control pulse to a control element of said device, means for applying said signal pulse to a control element of said device, a condenser connected to be rapidly discharged upon conduction of said device to thereby produce the steep wave front of the steep pulse.

5. A demodulator according to claim 2 wherein said current control means comprises an electron discharge device and further including means for impressing said delayed control pulse on said device to initiate conduction thereof, and means for impressing said steep pulse on said device for halting the conduction thereof.

6. A demodulator according to claim 2 wherein said means responsive to the coincidence of the delayed control pulse and the signal pulse comprises an electron discharge device having at least one control element biased so as to conduct upon

coincidence of the control pulse and the signal pulse, means for applying said delayed control pulse to a control element of said device, means for applying said signal pulse to a control element of said device, a condenser connected to be rapidly discharged upon conduction of said device to thereby produce a negative pulse having a steep wave front, and said current-control means comprises a second electron discharge device, means for impressing said control pulse on a grid of said second device to cause conduction thereof, and means for impressing the steep negative pulse upon a grid of said electron discharge device to halt conduction thereof.

7. A channel selector and demodulator for multi-channel time modulation pulse systems of the type in which a marker signal is followed by a succession of signal pulses, each forming part of a separate channel and each varying from a given time position with respect to the marker signal according to its modulation, comprising means responsive to the marker pulse for producing a control pulse of constant duration, said duration being at least as great as the maximum range of time displacement of the signal pulses due to modulation, means for delaying said control pulse to coincide with a pulse of the channel desired so that the control pulse has a fixed time relationship to the unmodulated position of the signal pulse and covers the entire range of time displacement thereof, means responsive to the coincidence of the delayed control pulse and the signal pulse of the desired channel to produce a pulse having a steep wave front, current-control means responsive to the leading edge of the delayed control pulse for initiating the flow of current and responsive to the steep pulse for halting the flow of current, the resultant output pulse from said current control means varying in duration in accordance with the time modulation of the signal pulse of the desired channel,

and integrating means for translating the duration of said output pulse into an amplitude characteristic.

8. A channel selector and demodulator according to claim 7 wherein said means responsive to the coincidence of the delayed control pulse and the signal pulse of the desired channel comprises an electron discharge device having at least one control element, means for biasing said device so that it conducts upon coincidence of the control pulse and signal pulse, means for applying said control pulse and said signal pulse to control the conduction of said device, a condenser connected to be rapidly discharged upon conduction of said device to thereby produce the steep wave front of the steep pulse.

9. A channel selector and demodulator according to claim 7 wherein said current control means comprises an electron discharge device, means for applying said control pulse so that the leading edge thereof initiates conduction of said device, said control pulse having a duration at least equal to the total width of the signal pulse plus the total period covered by the time displacement of the pulse, and means for applying the steep pulse to halt conduction of said device, said steep pulse having a greater amplitude and an opposite vectorial direction with respect to said control pulse.
